Filed Mar. 16, 1961, Ser. No. 64,333

Term of patent 14 years

(Cl. D81—10)

FIG. 1 is a perspective view of a handle for frying pan, showing our new design, the pan shown in broken lines being included for purposes of illustration only.

FIG. 2 is an enlarged top plan view of the handle for frying pan shown in FIG. 1;

FIG. 3 is an enlarged side elevational view thereof as shown in FIG. 2; and

FIG. 4 is an enlarged front elevational view thereof as shown in FIG. 2.

The dominant features of our design reside in the portions shown in full lines.

We claim:

The ornamental design for a handle for frying pan, as shown and described.
